UNITED STATES PATENT OFFICE.

LOUIS P. ROBITOY, OF FARGO, NORTH DAKOTA, AND CHARLES L. VELANDER, OF MINNEAPOLIS, MINNESOTA, ASSIGNEES TO UNDERWOOD TYPEWRITER COMPANY, OF NEW YORK, N. Y., A CORPORATION OF DELAWARE.

TYPEWRITING MACHINE.

Application filed October 30, 1923. Serial No. 671,643.

To all whom it may concern:

Be it known that we, LOUIS P. ROBITOY and CHARLES L. VELANDER, both citizens of the United States, said ROBITOY residing in 5 FARGO, county of Cass, and State of North Dakota, and said VELANDER residing in Minneapolis, county of Hennepin, and State of Minnesota, have invented certain new and useful Improvements in Typewriting Machines, of which the following is a specification.

This invention relates to machines for 15 typing upon a number of superposed webs or continuous sheets, especially those in the use of which it is intended to tear off section after section from the body of a web, carbon-sheets being placed between the plies of the web, and being pulled back from time to time relatively to the web, as disclosed in 20 patent to Wernery & Smith, No. 1,132,055.

To obtain records of the numerous successive forms closely succeeding one another, a condensed record-sheet is, according to the 25 present improvements, held stationary while the webs or plies outside thereof are advanced in the machine, at the conclusion of the typing of each form.

The record-sheet is entirely separate from 30 the superposed web plies, and may be inserted while the webs and carbons remain in the machine, and when inserted at the introductory side of the platen, is guided around the latter by said webs and carbons to the delivery side of the platen adjacent 35 the lower edge of a front paper-table.

Preferably, the insertion of the record-sheet is effected when the webs are in 40 straightened position beneath the platen. The lower edge of the paper-table, however, lies close to the platen; and, by the present invention, provision is made of means whereby the leading edge of the record-sheet will be guided between the rear of the paper-table and the platen. To this end, a guide-plate 45 is fastened to the rear side of the front paper-table extending considerably beyond the lower edge thereof, which has a paper-finger-guide on one side of its bottom edge, so arranged that, when the record-

sheet is thrust forward and skewed with the 50 corresponding front corner in advanced position, the advanced corner will pass back of the end of the guiding finger, and will be guided thereby between the rear of said paper-table and the platen. The superposed 55 web and associated carbon will support the record-sheet until the leading edge thereof passes over the extended guide-plate to insure the passage of the leading edge of the record-sheet to its proper position. Following 60 the introduction of one corner of the record-sheet between the lower edge of the extended guide-plate and the platen, further advance of the record-sheet will cause its inclined leading edge to ride over the lower 65 edge of the guide-plate until the entire leading end of the record-sheet lies between the lower edge of the guide-plate and the platen throughout its whole width. The record- 70 sheet may then be correctly adjusted in position both longitudinally and transversely 75 relatively to the position of the web in the machine. To assist in aligning the record-sheet when so introduced, provision may be made of side gages at the rear of the front paper-table.

When a record-sheet is to be inserted, the paper-table is preferably swung to horizontal position to permit the work-form and associated carbons to be straightened beneath the platen, and the record-sheet is thrust forward from the rear and guided by means of the offset guiding finger and extended guide-plate to the rear of the front paper-table, a finger-piece on the back of the paper-table being depressed to permit the leading edge of the record-sheet to pass between a holding clamp and the guide-plate. In such movement of the record-sheet, its leading edge may engage the lower end of the usual gage-bar or the usual screw by which the gage-bar is attached to the rear of the paper-table. To prevent such interference with the forward movement of the record-sheet, provision may be made of means to deflect the leading edge of the record-sheet over the ends of the gage-bar and its attached screw. Preferably, said deflecting means

comprises two deflectors, one on each side of the gage-bar, formed as hereinafter described.

The present invention is an improvement 5 over a similar novel feature disclosed in the co-pending application of Jesse A. B. Smith, Serial No. 558,139, filed May 3, 1922.

One object of the present invention is to 10 provide a novel, effective and simple means for easily guiding the condensed record sheet to its proper place, by making the paper-guide-finger integral with the guide-plate extending lengthwise of the platen, and making said guide-plate reach considerably 15 beyond the lower edge of the forward paper-table, so as to avoid catching the edge of the record-sheet, which may otherwise result, the guide-finger being located to one side of the normal position of 20 the web.

This improved inserting feature may be utilized by itself or in other combinations than herein described.

Another important novel feature is to 25 provide, on the guide-plate, a receiving edge which is sufficiently extended beyond the lower edge of the paper-table to reach a position forward of the cutting edge of the usual knife, so as to obviate trouble that 30 may be caused as a result of the engagement of the leading edge of the bottom carbon with the lower edge of the table, and to aid in guiding the composite work-form to the front side of the paper-table. All the carbon-sheets can then be made of uniform 35 length to reach over the extended edge of the guide-plate but below the cutting edge of the knife, when the carbon-carrier is in its rearmost position. The tearing off of 40 the work-form from the web is thus not interfered with, and the proper feeding over the paper-table of the work-form and the bottom carbon-sheet is insured when the same are advanced by the platen. This 45 feature may be applied to all forms of typewriters whether or not they have adjustable platens.

Other features and advantages will hereinafter appear.

50 In the accompanying drawings,

Figure 1 is a diagrammatic view, partly in section, of the invention applied to the platen-carriage of an Underwood typewriter, including a rearward extension on 55 which the carbon-carrier travels.

Figure 2 is a view similar to Figure 1, but showing the platen displaced and the front paper-table in substantially horizontal position after inserting the condensed record-sheet between the rear of the paper-table and the platen.

Figure 3 is a top plan view showing the 60 platen in displaced position corresponding to that shown in Figure 2, and indicating the manner in which the record-sheet is

introduced so as to pass between the extended guide-plate on the rear of the front paper-table and the platen.

Figure 4 is a fragment of the top plan view corresponding to Figure 1. 70

A platen 10 is fixed upon a shaft or axle 11, journaled in ends 12 and 13 of a platen-displacing frame 14. The ends 12 and 13 of the platen-displacing frame 14 are pivoted upon a rod 15, which, in turn, is supported at its ends by end plates 16 and 17 of a typewriter-carriage 18. The typewriter-carriage also includes a rear paper-table 19, and carries front and rear feed-rolls 20 and 21, respectively, to co-operate 75 with the platen in its normal position for feeding work-sheets therearound.

To turn the platen 10, provision is made of a stub-shaft 22 journaled in the end plate 16 of the carriage, and having at its inner end a gear 23 meshing with a broad pinion 24 on the rod 15. The broad pinion 24 also meshes with a gear 25 at the left-hand end of the platen-axle, the gear 25 being of the same size as the gear 23. The 80 platen may be rotated by the stub-shaft 22 through a finger-wheel 26 thereon attached, or by the usual line-spacing means, not shown. A similar gearing provision may 85 also be made at the right end of the carriage.

Connected to a cross-bar 32 of the carriage 18, by means of brackets 33, is a rearward extension 34 of the carriage 18, said rearward extension comprising rails 35 on which run grooved wheels 36 on the bottom of a carbon-carrier 37. The carbon-carrier 37 comprises carbon holders or bars 38, to which the rear ends of carbon-sheets 39 are attached, and between which webs or work-sheets 40 are threaded. 100

The webs 40 and interleaved carbon-sheets 39 extend forwardly between side gages 43 mounted on a rock-shaft 51. Then webs 40 and carbon-sheets 39 pass over a raised portion 44 of the rear paper-table 19 and between the latter and the platen around to the delivery side of the latter. From the delivery side of the platen the webs pass 110

upwardly between the platen and the usual knife 45, which is mounted to be swung within slight limits by a knife-actuating rod 29. The paper-table 46 is rigidly supported by a cross-bar 47, forming part of the platen-swing-frame and also constituting, in effect, a part of the front paper-table 46. A deflector-plate 72, having deflectors 74 formed thereon, is secured at one side of the cross-bar 47 and the paper-table 46 is secured at the other side of the cross-bar 47. A guide-plate 71, having a guide-finger 70 integral therewith, extending considerably beyond the lower edge of the paper-table 46, forms the rear side of the front paper-table. The deflector-plate 72, 120

- the guide-plate 71 and the paper-table 46 are fastened to the cross-bar 47 in any suitable manner, as by screws 30 and nuts 31. A gage-bar 48, of the usual form, is 5 detachably secured to the rear side of the paper-table 46 by suitable means, such as a screw 49, having a knurled head. An adjustable gage 50, of the usual type, is mounted on the gage-bar 48.
- 10 The rock-shaft 51 extends across the carriage beneath the raised portion 44 of the rear paper-table, and is journaled in the ends 16 and 17 of the carriage 18. When the platen-displacing frame 14 is in its normal 15 position, the ends 12 and 13 thereof rest on the shaft 51, and the frame 14 is held in this position by left and right hand latches 52 and 53, respectively. The latches are fixed upon the shaft 51 and co-operate with studs 20 52^a and 53^a, projecting inwardly from the ends 12 and 13, respectively, to hold the frame 14 in its normal position. This shaft is normally urged to swing the latches 52 and 53 to effective position by means of coil 25 springs 54 and 55 at the left and right ends, respectively, of the shaft 51. To release the latches, provision is made of a finger-piece 56 forming an extension of the left-hand latch 52.
- 30 Each of the webs 40 may consist of a succession of similar forms, and, upon completion of the typing on one set of superposed forms, the webs must be advanced sufficiently to enable the set of used forms to 35 be severed. It is desirable, however, to have carbon-copies of the matter typed on the different sets of forms in condensed form on a single record-sheet 57. To obtain this result, the record-sheet must be held against 40 movement while the webs are advanced to the severing position at the conclusion of the typing of each set of superposed forms. The record-sheet 57 is therefore clamped against movement with reference to the 45 paper-table 46. To do this, means are provided, such as a bail 58, having arms 59, pivoted on screws 60, threaded into the ends 12 and 13 of the platen-displacing frame 14, and a cross-bar 61, having thereon friction 50 members 62 of suitable material, such as rubber, to co-operate with the guide-plate 71 at the back of the paper-table 46 to grip the record-sheet 57 to the guide-plate 71. The bail 58 is kept in effective position by 55 springs 63. Each arm 59, at the rear of the screw 60, on which it is pivoted, curves upwardly and forwardly, and at its end is provided with a stud 64 in the path of the hook-portion of the adjacent latches 52 and 53, so that, when the frame 14 is in its normal 60 position and said latches 52 and 53 are swung to effective position, the bail 58 will be swung to ineffective position, to enable the record-sheet 57 to be fed by the platen. Provision may also be made of finger-pieces
- 65 mounted on the arms 59 whereby the clamping bail may be moved to ineffective position.
- The lower edge of the paper-table 46 ordinarily would lie very close to the platen 10. In order to facilitate the guiding of the leading edge of the record-sheet 57, inserted from the rear between the carbons 39 and webs 40 and the platen, to pass to the rear of the paper-table 46, the extended 70 guide-plate 71 and the guiding finger are provided. As shown in Figure 2, the finger 70 and the shaped guide-plate 71 form simple means, extending beyond the rear edge of the paper-table 46, so as to avoid 75 catching the edge of the record-sheet that may otherwise result. The finger 70 is located to one side of the normal position of the work-form (see Figures 3 and 4), so as not to interfere therewith as it advances over 80 the front of the paper-table 46, and also to render it readily accessible.
- When a record-sheet 57 is to be inserted, the finger-piece 56 is swung to the rear to 85 release the platen-displacing frame 14, and the latter is swung forwardly around the rod 15 until the paper-table 46 rests upon an abutment 75 on the front rail 76 of the carriage 18. Preferably the abutment 75 is of yielding material, such as rubber. It 90 is to be understood that at this time the webs 40 are in proper position for starting typing on a new form and the carbons 39 are in retracted position. At this time the webs 40 and the carbons 39 will be supported 95 in proper position relative to the paper-table 46 by means of the usual knife 45. When, therefore, the record-sheet is inserted at the rear of the platen between the webs 40 and the carbon-sheets 39 on one hand and the platen 10 on the other, as indicated in 100 Figures 2 and 3, the left-hand forward corner of the sheet will be directed above the end of the finger 70, and will easily pass the receiving edge of the guide-plate 71 to the rear of the paper-table 46. As shown in 105 Figure 3, the record-sheet 57 is thrust forward with its leading edge in inclined position, and it will be evident that, after the left forward corner has been introduced between the rear of the paper-table 46 and the platen, further movement of the record-sheet 57 will cause the inclined leading edge of the same to ride over the lower edge of 110 the guide-plate 71 and pass between the latter and the platen. The record-sheet may then be straightened and aligned with the work-form in the machine.
- When the paper-table 46 is in the position shown in Figure 2, the clamping bail 58 will be in effective position. It is desirable, however, that the record-sheet 57, as it is guided between the paper-table 46 and the platen 10, be allowed to pass along 115 the rear face of the paper-table 46. To per-
- 120
- 125
- 130

mit such action, either finger-piece 65 may be depressed to shift the clamping bail 58 to ineffective position. Further movement of the record-sheet 57 (see Figure 2) serves 5 to move the latter between the clamping bail and the guide-plate 71 at the rear of the paper-table 46. It will be seen that the finger 70 will guide the leading edge of the record-sheet 57 to the rear of the paper-table 46. When the record-sheet 57 is properly adjusted, the finger-piece 65 may be released to permit the clamping bail 58 to press the record-sheet against the guide-plate 71 and hold it fixed relatively thereto. The frame 14 may then be swung to 10 its normal position and there held by means of the latches 52 and 53; the latter, in their movement to effective position, releasing the record-sheet 57 so as to be fed with the webs 40 upon line-space movement of the platen. After the insertion of the record-sheet 57, as just explained, and upon the return of the platen 10 to its normal position, 15 typing may be effected on the properly positioned set of superposed forms in the usual manner, and, upon the completion of such typing, the displacing frame 14 may be swung forwardly to the position shown in Figure 2, the clamping bail 58 being made effective automatically upon the 20 releasing of the frame 14 by the latches 52 and 53. The webs 40 may be drawn forwardly and gaged by means of the gage 50, and the carbon-sheets 39 restored to 25 their rearward position by means of the carbon-carrier 37. The platen may then be restored to its normal position and the used forms severed over the knife 45, this 30 operation being repeated for each set of superposed forms.

To prevent fouling of the record-sheet 57 when moved past the bar 61 of the clamping bail, through the normal tendency of the forward edge of the record-sheet to engage the screw 49, by which the gage-bar 48 is secured to the rear of the paper-table 46, provision has been made of suitable inclined deflectors 74 formed of a stamped tongue section of the supporting 45 deflector-plate 72 and which pass upwardly 50 through the openings in the guide-plate 71 on opposite sides of the gage-bar 48.

The above-disclosed improvement in the 55 condensed record-sheet-inserting mechanism includes the novel designed co-operating guide-plate 71 extending considerably beyond the lower edge of the paper-table 46, shaped and proportioned not only to enable 60 easy and quick insertion of the record-sheet 57 so as to avoid catching of the edge of the record-sheet 57 with the lower edge of the paper-table 46, which may otherwise happen, but also to obviate the trouble that may 65 be caused as a result of the engagement of the leading edge of the bottom carbon 39

with the lower edge of the paper-table 46. The receiving edge of the guide-plate 71 extends sufficiently beyond the lower edge of the paper-table 46 to reach a position in advance of the cutting edge of the knife 45, 70 see Figure 1. All the carbon-sheets 39 may be made to have a uniform reach over the extended edge of the guide-plate 71 at the platen end, but must be limited to extend below the knife-edge when the carbon-carrier 37 is in its rearward position. The tearing of sections from the web will not be interfered with and proper feeding of the work-form and of the bottom carbon 39 over the paper-table 46 will be insured when 75 advanced by the platen.

Variations may be resorted to within the scope of the invention, and portions of the improvements may be used without others.

Having thus described our invention, we claim:

1. In a composite web typewriting machine having a displaceable platen and typing instrumentalities, a work-table at the delivery side of the platen, means operative during displacement of the platen to support the composite web and permit straightening thereof beneath the platen, a chute-plate secured at the rear of said work-table to extend beyond the end thereof contiguous to the platen, and a sheet-introductory member projecting beyond the chute-plate to receive a record-sheet inserted between said platen and said sheet-introductory member and guide said record-sheet over the receiving edge of said chute-plate.

2. In a composite web typewriting machine having a displaceable platen and typing instrumentalities, a work-table at the delivery side of the platen, means operative during displacement of the platen to support the composite web and permit straightening thereof beneath the displaced platen, a chute-plate secured at the rear of said work-table to extend rearwardly beyond the end thereof contiguous to the platen and lengthwise of the platen, and a sheet-introductory guide-finger at one side of said chute-plate co-operative with the platen to form a bite with the leading portion of a canted record-sheet and guide said record-sheet over the receiving edge of said chute-plate behind said work-table.

3. In a composite web typewriting machine having a displaceable platen and typing instrumentalities, a work-table at the delivery side of the platen, means operative during displacement of the platen to support the composite web and permit straightening thereof beneath the platen, a chute-plate secured at the rear of said work-table to extend beyond the end thereof contiguous to the platen, a sheet-introductory member projecting beyond the chute-plate to receive a

record-sheet inserted between said platen and said sheet-introductory member and guide said record-sheet over the receiving edge of said chute-plate, and a sheet-deflector at the rear of said work-table to direct the leading edge of said record-sheet rearwardly over the platen, said work-table including means to restrain feeding movement of said record-sheet during a composite web-shifting operation.

4. In a composite web typewriting machine having a displaceable platen and typing instrumentalities, a work-table at the delivery side of the platen, means operative during displacement of the platen to support the composite web and permit straightening thereof beneath the platen, a chute-plate secured at the rear of said work-table to extend beyond the end thereof contiguous to the platen, a sheet-introductory member projecting beyond the chute-plate to receive a record-sheet inserted between said platen and said sheet-introductory member and guide said record-sheet over the receiving edge of said chute-plate, and a sheet-deflector at the rear of said work-table to direct the leading edge of said record-sheet rearwardly over the platen, said sheet-deflector comprising a bent tongue extending from the rear of said work-table through an opening in said chute-plate.

5. In a composite web typewriting machine having a displaceable platen and typing instrumentalities, a work-table at the delivery side of the platen, means operative during displacement of the platen to support the composite web and permit straightening thereof beneath the displaced platen, a chute-plate secured at the rear of said work-table to extend rearwardly beyond the end thereof contiguous to the platen and lengthwise of the platen, a sheet-introductory guide-finger at one side of said chute-plate co-operative with the platen to form a bite with the leading portion of a canted record-sheet and guide said record-sheet over the receiving edge of said chute-plate behind said work-table, and a sheet-deflector at the rear of said work-table to direct the leading edge of said record-sheet rearwardly over the platen, said sheet-deflector comprising a bent tongue extending from the rear of said work-table through an opening in said chute-plate, said work-table including means to restrain feeding movement of said record-sheet during a composite web-shifting operation.

6. In a composite web-typewriting machine having a displaceable platen and typing instrumentalities, a work-table at the delivery side of the platen, means operative during displacement of the platen to support the composite web and permit straightening thereof beneath the platen, a chute-plate secured at the rear of said work-table to ex-

tend beyond the end thereof contiguous to the platen, and a sheet-introductory member projecting beyond the chute-plate to receive a record-sheet inserted between said platen and said sheet-introductory member, and guide said record-sheet over the receiving edge of said chute-plate, said composite web-supporting means overlapping the receiving edge of said chute-plate and providing a continuous path of feed for said record-sheet.

7. In a composite web typewriting machine having a displaceable platen and typing instrumentalities, a work-table at the delivery side of the platen, means operative during displacement of the platen to support the composite web and permit straightening thereof beneath the displaced platen, a chute-plate secured at the rear of said work-table to extend rearwardly beyond the end thereof contiguous to the platen and lengthwise of the platen, and a sheet-introductory guide-finger at one side of said chute-plate co-operative with the platen to form a bite with the leading portion of a canted record-sheet and guide said record-sheet over the receiving edge of said chute-plate behind said work-table, said composite web supporting means overlapping the receiving edge of said chute-plate and providing a continuous path of feed for said record-sheet.

8. The combination with the platen of a typewriting machine, having a main chute for guiding a main work-sheet, of a supplementary sheet-inserter, comprising a chute-plate extending longitudinally of the platen above said main chute, said chute-plate having an integral portion co-operative with the platen to form a bite upon the inserted portion of a canted supplementary sheet and guide said supplementary sheet on to the said chute-plate.

9. The combination with a typewriting machine including a platen, typing instrumentalities, a work-table at the delivery side of the platen and a main chute for guiding a work-sheet from the rear of the platen to the front of said work-table, of a supplementary chute-attachment comprising a chute-plate detachably mounted on said work-table to extend above said main chute, a guide-finger integral with said chute-plate co-operative with the platen to form a bite for the leading portion of a canted supplementary sheet and guide said supplementary sheet over the receiving edge of said chute-plate behind the work-table.

10. The combination with a typewriting machine including a platen, typing instrumentalities, a work-table at the delivery side of the platen and a main chute for guiding a work-sheet from the rear of the platen to the front of said work-table, of a supplementary sheet-inserter comprising a chute-plate

- detachably mounted on said work-table to extend above said main chute, a guide-finger integral with said chute-plate co-operative with the platen to form a bite for the leading portion of a canted supplementary sheet and guide said supplementary sheet over the receiving edge of said chute-plate to the rear of said work-table, and clamping means to restrain feeding movement of said supplementary sheet when said main sheet is freed from the platen and shifted.
11. In a typewriting machine for writing upon a number of interleaved carbon superposed webs or continuous sheets, in combination, a platen, a front paper-table for receiving the composite webs fed around the platen on the front side thereof, a guide-plate extending lengthwise and adjacent the platen beyond the lower edge of said paper-table for directing the composite webs to the front side of the paper-table and a record-sheet to the rear side of the same, and a knife extending over and across the webs mounted in fixed spaced relation to the guide-plate, said guide-plate having a receiving edge extending forward of the cutting edge of the knife to insure proper feeding over the paper-table of said webs with the bottom carbon-sheet when the same are advanced by the platen after tearing off a section of the webs.
12. The combination with a typewriting machine including a platen, typing instrumentalities, a work-table at the delivery side of the platen and a main chute for guiding a work-sheet from the rear of the platen to the front of said work-table, of a supplementary sheet-inserter comprising a chute-plate detachably mounted on said work-table to extend above said main chute, a guide-finger integral with said chute-plate and at one side of the latter co-operative with the platen to form a bite for the leading portion of a canted supplementary sheet and guide said supplementary sheet over the receiving edge of said chute-plate to the rear of said work-table, deflecting means at the rear of said work-table to direct the leading edge of said supplementary sheet rearwardly over the platen during feeding movement, and clamping means to restrain feeding movement of said supplementary sheet when said main sheet is freed from the platen and shifted.
13. As an article of manufacture, a supplementary chute-attachment for a typewriting machine having a platen and a work-table, comprising a deflector-plate having a plurality of deflectors, a chute-plate co-operative with said deflector-plate and having openings to receive said deflectors, and a guide-finger on said chute-plate, said chute-plate and deflector-plate constituting a unit.
14. As an article of manufacture, a supplementary chute-attachment for a typewriting machine having a platen and a work-table, comprising a deflector-plate having a plurality of integral deflectors, a chute-plate co-operative with said deflector-plate and having openings to receive said deflectors, and an integral finger on said chute-plate, said chute-plate and deflector-plate constituting a unit.
15. A supplementary chute-attachment for a composite web typewriting machine including a displaceable platen and a work-table displaceable with the platen, comprising a deflector-plate having a plurality of deflectors struck outwardly from the body thereof, a chute-plate co-operative with said deflector-plate and having openings to receive said deflectors, and an integral guide-finger on said chute-plate, said chute-plate and deflector-plate being attachable as a unit to said work-table.
16. A supplementary chute-attachment for a composite web typewriting machine including a displaceable platen and a work-table displaceable with the platen, comprising a deflector-plate having a plurality of deflectors struck outwardly from the body thereof, a chute-plate co-operative with said deflector-plate and having openings to receive said deflectors, and an integral guide-finger on said chute-plate, said chute-plate and deflector-plate being attachable as a unit to said work-table, said guide-finger co-operative with said platen to form a bite with an inserted portion of a record-sheet and guide said record-sheet over said chute-plate, and said deflectors inclined to direct the leading edge of the record-sheet rearwardly over the platen.
17. A supplementary chute-attachment for a composite web typewriting machine including a displaceable platen and a work-table displaceable with the platen, comprising a deflector-plate having a plurality of deflectors struck outwardly from the body thereof, a chute-plate co-operative with said deflector-plate and having openings to receive said deflectors, an integral guide-finger on said chute-plate, said chute-plate and deflector-plate being attachable as a unit to said work-table, said guide-finger co-operative with said platen to form a bite with an inserted portion of a record-sheet and guide said record-sheet over said chute-plate, and said deflectors inclined to direct the leading edge of the record-sheet rearwardly over the platen, and means operative during displacement of said platen and work-table to clamp said record-sheet to said chute-plate.

LOUIS P. ROBITOY.
CHARLES L. VELANDER.
